LAST

Paul S. Jones, Brockton, Mass., assignor to Jones & Vining, Inc., Brockton, Mass., a corporation of Massachusetts

Application May 11, 1938, Serial No. 207,369

2 Claims. (Cl. 12—139)

My present invention is a novel and improved construction of last for use in the manufacture of boots and shoes, and is directed more particularly to protect and improve that portion 5 where the last thimble is fitted and to protect the wood of the last from damage or injury.

Heretofore, in the construction of lasts it is customary to bore a thimble-receiving recess in the heel portion of the last and, thereupon, to fit 10 within said recess a metal thimble which is wedged into the bored recess and usually fits solidly against the bottom of the bored opening. Thus, when the shoe is fitted on the pin of the last jack and the strains and stresses incident 15 to heel-nailing, sole-leveling, or the like are being performed on the shoe bottom and transmitted thru the thimble and top or cone of the last to the jack considerable pressure and strain is brought to bear upon these parts, often re- 20 sulting in damaging the wood not only at the cone but also at the end or bottom of the bored recess in which the thimble is fitted.

In order to aid in withstanding these pressures and protect the wood of the last, and in an 25 effort to increase the life of the last, it has often been customary to fit in rivets or bolts entirely thru the last, both at the base of the thimble recess and at the rear of the thimble.

It has also been customary to fit a protecting 30 layer, or layers, on the top or cone of the last, such as fibre, leather, or the like.

In all these prior efforts to protect and strengthen the last around the thimble portion, considerable difficulty has been experienced and 35 the various devices previously employed have been unsatisfactory in various ways. Thus, where a yielding protecting layer across the top of the last was employed with the solid thimble, the protecting layers would yield and bring most of 40 the strain on the thimble, which in turn would be wedged into the base of the recess.

My present invention contemplates a new and novel method of last and thimble protection which will enable the protecting layers on top of 45 the last around the thimble and the thimble itself to each yield to the proportionate extent necessary in transmitting the strain, stresses, and blows to which the last is necessarily subjected during use.

50 I believe that my invention of double yielding capacity for both a protecting layer and thimble, thus fully cooperating and, furthermore, yielding proportionately so that each part can take up a proper part of the load and strains transmitted therethru, is a distinct novelty in this art and

results in greatly increasing the life of the last and preventing damage and injury to the wood of the heel part.

In carrying out my invention, I provide a last with a protecting layer, or layers, on the top of 5 the cone, such as the usual combined fibre and leather protector top, and I arrange a thimble with capacity to yield with the yielding and compression of the protector top. Also I interlock the thimble with the protector top so that the 10 first strains and stresses coming on the protector will be partly transmitted to the thimble, as well as to the wood of the last, and as the protector top is still further compressed a fuller load will be picked up directly by the metal thimble itself, 15 which will then be in contact with the last jack, said thimble being arranged for independent yielding action, as well as in combination with the yielding of the protector top, thus presenting the combined results of both the protector and 20 the yielding support for the thimble within the last thru which the strain, stresses, and blows are transmitted and dissipated.

Referring to the drawing illustrating a preferred embodiment of my invention, 25

Fig. 1 is a side view of my improved last;

Fig. 2 is a top plan view, and

Fig. 3 is an enlarged cross-sectional view of the heel portion.

While I have illustrated herein my invention 30 as applied to a typical type of hinge last, it will be appreciated that the invention may be embodied with equal advantage in any type of last, whether a hinge last, solid last, or block last, or indeed in any last construction wherein a thimble is fitted in the heel portion to enable the last 35 to be applied to a last jack and pin.

As shown in the drawing, I illustrate a typical hinge last, usually made of rock maple, comprising a forepart 1 and a heel portion 2 united with 40 any suitable hinge construction on the axis, or pivot, approximately as shown at 3. The heel part 2 is formed with a top or cone portion 5 considerably narrowed, as is customary, in accordance with the design or style of last construction, 45 on which a protector top of one or more layers, herein shown as two layers, viz. fibre 7 and leather 8, which are usually glued or united together and secured to the cone of the last by a plurality of nails or screws 9—9.

In the heel portion is bored a thimble-receiving recess 10, and a corresponding aperture 12 to register with the recess 10 is provided in the layers of the protector top. In my invention I form this opening 12 in the protector top of less di- 50 55

ameter than that of the thimble-receiving recess 10, and I provide a novel thimble 15 having its outer diameter adapted to fit slidingly the recess 10, and with a reduced part and shoulder portion 16 to fit in the opening 12, thus providing an interlocking construction between the protector layers and the thimble 15.

Also I form the opening 10 of greater depth than the length of the thimble 15 and fit in the bottom of the recess 10 a coiled expansible spring 18 adapted to bear upon the bottom of the thimble 15. Preferably, also I may fit a metal washer 20 in the bottom of the recess 10 to act as a bearing member for the end of the spring 18 opposite to the thimble-contacting end.

As thus constructed and arranged, it will be appreciated that the combined resilience of the protector top and layers and spring 18 will act to cushion the blows, strains, and stresses necessarily transmitted thru the bottom of the last to the jack on which it rests during heel-nailing, sole-leveling, and the like operations, so that the entire wood portion of the heel is yieldingly sustained both at the top or cone 5 and at the bottom of the thimble recess. Therefore, the wood in the heel portion is protected against damaging blows, and a cushioning construction thru the protector top and thru the thimble is afforded.

While I prefer to employ a cushioning member 30 for the thimble, such as the coiled spring 18, it might be feasible to utilize a block of rubber or any other yielding and supporting cushioning means.

The feature of the shoulder 16 is most important as it enables the thimble to slide in interlocking cooperation with the protector and under the tension of the spring 18.

Furthermore, the thimble is held against being displaced by the spring 18 thru this interlocking construction of the protector top bearing on the shoulder 16. Also, it facilitates the assembling operations. The washer 20 is preferably first fitted in the bottom of the recess 10 and thereupon the coiled spring 18 or other cushioning member is dropped into position and the thimble 15 applied; whereupon the protector top is fitted over the reduced open end of the thimble 15 until the same bears on the shoulder 16, whereupon the spring 18 may be compressed during the further fitting of the protector top to the last by driving down the fastening means, such as nails or the screws 9, as illustrated.

The importance and desirability of my improved last construction with yielding and cushioning means, both for the top of the last and the thimble, which furthermore are interlocked to cooperate in effecting such cushioning action, will be readily appreciated by those skilled in this art.

I claim:

1. An improved last having in combination a yielding protecting member and yielding thimble-supporting means, in combination with an interlocking construction between said thimble and the protector.

2. As an improved article of manufacture, a thimble for fitting in the heel portions of lasts, comprising a tubular portion of suitable diameter to fit the thimble-receiving recess in the last, and a portion reduced in diameter at the top of the thimble, in combination with a protector member at the top of the last adapted to engage said reduced portion.

PAUL S. JONES.
